UNITED STATES PATENT OFFICE.

JOSEPH J. MIZER, OF RACINE, WISCONSIN, ASSIGNOR TO WALKER MANUFACTURING COMPANY, OF RACINE, WISCONSIN, A CORPORATION OF WISCONSIN.

LIFTING JACK.

Application filed November 7, 1921. Serial No. 513,341.

To all whom it may concern:

Be it known that I, JOSEPH J. MIZER, a citizen of the United States, residing at Racine, in the county of Racine and State 5 of Wisconsin, have invented certain new and useful Improvements in Lifting Jacks, of which the following is a specification.

My invention relates to lifting jacks and it has for its principal object the provision 10 of a new and improved arrangement and construction comprising two telescoping screws by which the load supporting member is raised and lowered. It is one of the objects of my invention to provide a construction 15 of this type in which such screws operate successively, the friction in the operation of the device being thus restricted to a single screw at any given point in the operation while at the same time the reach of 20 the jack as a whole corresponds to that of the well known double screw jacks in which both screws are operated at the same time with a consequent heavy friction. It is another object of my invention to provide in 25 a jack of this type for swinging the operating handle around a vertical axis with respect to the standard so as to provide for the positioning of the handle at the most convenient point for operation on a particular job. It is still another object of my invention to provide that such adjustment of 30 the position of the handle can be effected at any time during the raising operation. It is another object of my invention to improve 35 devices of this type in sundry details hereinafter pointed out. The preferred means by which I have accomplished my several objects are illustrated in the drawings and are hereinafter specifically described. That 40 which I believe to be new and desire to cover by Letters Patent is set forth in the claims.

In the drawings,—

Fig. 1 is a central vertical section through the preferred embodiment of my invention.

Fig. 2 is a side elevation of the lower end portion of the jack and

Fig. 3 is a horizontal section taken at line 3—3 of Fig. 2.

Referring to the several figures of the 50 drawings in which corresponding parts are indicated by the same reference characters, 10 indicates a standard in the form of a sleeve cast integrally with a base 11. The upper end of the sleeve 10 is in the form of a nut, being provided with interior screw

threads for cooperation with a hollow screw 12. Mounted upon the upper end of the screw 12 is an anti-friction thrust bearing 13 of any approved type, above which is mounted a second nut 14 which is thus supported by the screw 12. Loosely mounted within the hollow screw 12 and extending through the central opening of the bearing 13 is a second screw 15, the threads of the screw 15 being in operative engagement with the threads of the nut 14 whereby the screw 15 is also supported from the screw 12. Upon the upper end of the screw 15 there is revolvably mounted a load supporting member 16 of any approved type, a thrust bearing 17 being interposed between the load supporting member and the screw.

Revolvably mounted upon the nut 14 is a cap 18 which forms the upper closure member of a housing 19 which extends about the standard 10 in spaced relation thereto. It will be appreciated that by mounting the housing 19 upon the nut 14 such housing will be supported by the hollow screw 12. For rotating the nut 14 for effecting the operation of the jack as hereinafter described, I have formed integrally with the nut a beveled gear 20 which meshes with a beveled gear 21 keyed upon a shaft 22 which is journalled in a suitable bearing provided by the housing 19. A thrust bearing 23 of any suitable type is interposed between the beveled gear 21 and the wall of the housing. Mounted upon the outer end of the shaft 22 for rotating it there is a hand crank or lever 24 of any approved type.

As is clearly shown in Fig. 1, the hollow screw 12 is provided at one side with a vertically extending slot 25 within which a pin 26 extends from one side of the inner screw 15 and is free to move vertically therein.

With the parts in the position shown in Fig. 1, the jack is adapted to be placed in position beneath a load to be raised, as will be readily understood. As is clearly shown in Figs. 2 and 3, the outer wall of the standard 10 is fluted vertically so as to provide a plurality of vertically extending grooves into any one of which a screw 27 carried by the housing 19 is adapted to be projected by rotating the screw through the medium of the head 28. When the jack has been placed in position under a load, the screw 27 can be retracted so as to permit the hous-

ing 19 to be rotated with respect to the standard 10 for bringing the hand crank 24 to the most convenient position for operation, the handle 24 being left free to rotate 5 so as to permit the gear 21 to travel about the gear 20. When the housing has been rotated to the desired point, the screw 27 is again moved into position to enter the adjacent vertical groove of the standard 10 10 for preventing further rotation of the housing 19 while at the same time permitting vertical movement of the housing as herein-after described.

When the jack has been adjusted to operative position, power is applied through the hand crank 24 for rotating the shaft 22 and the gear 21, serving to cause a rotation of the gear 20 and the nut 14 for causing an upward movement of the inner screw 15 15 with respect to the outer screw 12. As will be readily appreciated, this upward movement of the screw 15 with respect to the screw 12 is effected independently of any rotation of either screw, the screw 12 re- 20 maining stationary while the screw 15 moves upward carrying the pin 26 upwardly along the slot 25. When the pin 26 reaches the upper end of the slot 25, however, the inner screw 15 is held against further upward 25 movement with respect to the screw 12, whereupon the continued rotation of the nut 14 in the same direction as before causes the two screws to rotate in unison, causing the screw 12 to move upwardly through the 30 nut portion of the standard 10. It is thus seen that the screws 12 and 15 are moved upwardly in succession. That is to say, the screw 15 is first moved upwardly while the screw 12 is stationary, and the screw 12 35 is moved upwardly after the screw 15 reaches the limit of its upward movement with respect to the screw 12. The screw 15 continues to move upwardly after the screw 12 starts its upward movement, but this con- 40 tinued upward movement of the screw 15 is merely incidental to the support of the screw 15 by the screw 12. When it is desired to lower the load supporting member 45 16, this is effected by a rotation of the shaft 50 22 in the reverse direction through the me- 55 dium of the hand crank 24. As will be readily understood, upon the commencement of the reverse rotation of the nut 14 for a lowering operation, the screw 15 is first 60 moved downwardly to the limit of its motion with respect to the screw 12 during which movement neither of the screws is caused to rotate. When the screw 15 reaches the limit of its downward movement with 65 respect to the screw 12, the continued re- 70 verse rotation of the nut 14 causes both screws to rotate in unison for carrying the screw 12 downwardly through the nut por- 75 tion of the standard 10.

65 Inasmuch as the load supporting member

16 is supported by the screw 12 independ- 80 ently of the housing 19, it will be apparent that the adjustment of the housing 19 about its vertical axis can be effected at any time during the raising operation for adjusting 70 the position of the hand crank 24 without affecting in any way the raising operation.

I claim:

1. A lifting jack including in combination a standard, screws nested therein, means for moving said screws successively under cer- 75 tain conditions and together under other conditions, a housing rotatably mounted on and movable with one of said screws and enveloping said standard, and means carried by said housing for effecting movement of said screws in the desired manner.

2. A lifting jack comprising a standard, a screw supported by said standard, a second screw supported from said first named screw, 80 a load supporting member carried by said second screw, and means carried by the first named screw for raising said screws successively with respect to said standard.

3. A lifting jack comprising a standard, a screw supported by said standard, a second screw supported from said first named screw, 85 an anti-friction bearing interposed between said two screws, a load supporting member carried by said second screw, and means for 90 raising said screws successively with respect to said standard.

4. A lifting jack comprising a standard, a plurality of screws disposed one within another in said standard, means for preventing 100 relative rotation of said screws, a housing rotatably mounted on and movable with one of said screws and surrounding the standard, and means on said housing for causing longitudinal movement of said screws for load 105 lifting purposes.

5. A lifting jack comprising a standard, a screw supported by said standard, a second screw supported from said first named screw, 110 a load supporting member carried by said second screw, and a nut engaging said second screw and rotatably supported by said first-named screw.

6. A lifting jack comprising a base, a standard rising from the base, a hollow screw in threaded engagement with said standard, a nut supported on the upper end of said screw, a second screw in threaded engagement with said nut and extending into said first screw, said first and second screws 115 being provided with means for preventing relative rotation therebetween, a load supporting member on the end of said second screw, a housing supported by and depending from said nut surrounding said standard, and means carried by said housing in co- 120 operative engagement with said nut for rotating the latter to move said screws longitudinally for load lifting purposes.

7. A lifting jack comprising in combina- 125

tion a base, a standard rising from the base, a hollow screw in threaded engagement with said standard, a nut separate from and supported on the upper end of said screw, a second screw in threaded engagement with said nut and extending into said hollow screw, said first and second screws being provided with means for preventing relative rotation therebetween, a load supporting member on the end of said second screw, and means cooperating with said nut for rotating the same to move said screws for load moving purposes.

8. A lifting jack including in combination, an upright hollow standard, a hollow screw in threaded engagement with the upper end of said standard, a nut supported by said screw and separated therefrom by an anti-friction bearing, a second screw in threaded engagement with said nut and arranged to enter said first screw, a load engaging member carried by said second screw, a gear associated with said nut, a housing carried by and depending from said nut and surrounding said standard, a gear journaled in said housing cooperating with the first mentioned gear, and means exteriorly of the housing for actuating said gears to rotate said nut for moving said screws for lifting purposes.

9. A lifting jack comprising in combination a standard, a plurality of screws disposed one within another in said standard, means cooperating with said screws for preventing relative rotation therebetween and for limited vertical movement with respect to one another, a housing movable with one of said screws and surrounding said standard, means on said housing for causing longitudinal movement of said screws for load lifting purposes, said housing being adapted for rotative movement about its supporting screw for assuming different angular positions with respect to said standard, and means for locking said housing in adjusted angular position.

10. A lifting jack comprising a standard, a hollow screw supported by said standard and adapted upon rotation to move vertically with respect to the standard, a second screw loosely mounted within said first named screw, means for limiting the vertical movement of said second screw with respect to the first named screw and for holding said screws against rotation with respect to each other, a nut supported by said first named screw and engaging the threads of the second screw, a load supporting member carried by said second screw, a housing supported from said nut and slidably vertically with respect to said standard, means for holding said housing against rotation with respect to said standard, a hand crank mounted on said housing, and connections between said crank and said nut for rotat-

ing the nut adapted first to cause a vertical movement of the second screw to the limit of its motion with respect to the first named screw and adapted then to cause rotation of the screws in unison for raising them both with respect to the standard.

11. A lifting jack comprising a standard, a hollow screw supported by said standard and adapted upon rotation to move vertically with respect to the standard, a second screw loosely mounted within said first named screw, means for limiting the vertical movement of said second screw with respect to the first named screw and for holding said screws against rotation with respect to each other, a nut supported by said first named screw and engaging the threads of the second screw, a load supporting member carried by said second screw, a housing supported from said nut and slidably vertically with respect to said standard, means for holding said housing in any desired adjusted position about said standard, and operating means carried by said housing for rotating said nut adapted first to cause vertical movement of the second screw to the limit of its motion with respect to the first named screw and adapted then to cause rotation of the screws in unison for raising both of them with respect to the standard.

12. A lifting jack comprising a standard, a hollow screw supported by said standard and adapted upon rotation to move vertically with respect to the standard, a second screw loosely mounted within said first named screw, means for limiting the vertical movement of said second screw with respect to the first named screw and for holding said screws against rotation with respect to each other, a nut supported by said first named screw and engaging the threads of the second screw, a load supporting member carried by said second screw, a housing supported from said nut and slidably vertically with respect to said standard, means for holding said housing against rotation with respect to said standard, a gear carried by said nut, a shaft journaled in said housing at one side thereof, a gear fixedly mounted on said shaft and meshing with said first named gear, and means for rotating said shaft for driving said nut adapted first to cause vertical movement of the second screw to the limit of its motion with respect to the first named screw and adapted then to cause rotation of the screws in unison for raising them both with respect to the standard.

13. A lifting jack comprising a standard, a screw supported by said standard, a second screw supported from said first named screw, a load supporting member carried by said second screw, means adapted upon rotation in one direction to act alternately for raising both of said screws in unison and

- for raising one of the screws with respect to the other for carrying said load supporting member upwardly, means for operating said screw raising means, said operating means being adjustable about said standard independently of the load carried by said load supporting member, and means for locking said operating means in adjusted position.
- 10 14. A lifting jack comprising a standard, a screw supported by said standard, a second screw supported from said first named screw, a load supporting member carried by said second screw, means adapted upon rotation in one direction to act alternately 15 for raising both of said screws in unison and for raising one of the screws with respect to the other for carrying said load supporting member upwardly, means for operating said screw raising means, said operating means 20 being adjustable about said standard independently of any rotation of said rotary screw raising means, and means for locking said operating means in adjusted position.

JOSEPH J. MIZER.
